MULTI-V FM ANTENNA

Marvel W. Scheldorf, Palos Heights, Ill., assignor
to Andrew Corporation, Chicago, Ill., a corpora-
tion of Illinois

Application September 24, 1949, Serial No. 117,628

7 Claims. (Cl. 250—33.53)

1

The present invention relates to a radio transmitting antenna and more particularly, to a transmitting antenna designed for operation in the FM range of 88 to 108 megacycles.

Many broadcasting companies have obtained permits to transmit in the FM range in addition to the present AM frequency. It would be highly desirable to locate the FM transmitter at the AM transmitter site and to use the AM antenna tower for the FM antenna.

In making provision for a simple, lightweight and inexpensive FM transmitting antenna, it would be desirable to provide an arrangement whereby the antenna elements might be readily attached to the sides or corners of existing AM antenna towers or to a relatively short mast to be mounted at the top of an existing AM antenna tower. Such requirements necessitate an asymmetric construction which however, should provide in a horizontal plane a substantially circular radiation pattern.

In accordance with the present invention, a relatively simple, lightweight and inexpensive transmitting antenna for operation in the FM range is obtained by providing a plurality of bays, each of which has a shape corresponding generally to a truncated V. In an antenna of this type however, it is desirable to provide a driving impedance having a substantial value of the order of 50 ohms so as to minimize the matching problem in joining the antenna radiators to conventional transmission lines.

In order to realize further economies in the construction of an FM antenna, it is possible to provide radiating elements which are adjustable. Generally, however, such adjustable arrangements result in changes in both the horizontal radiation or field intensity pattern and variations in antenna impedance. Some of the pattern variations are not sufficiently severe but what they can be tolerated. However, impedance variations and changes require additional adjustable elements such as a multiplicity of matching elements or tuneable stubs. In accordance with the present invention however, it has been found possible to tune an antenna for resonance for any desired frequency of transmission without any substantial change in the antenna impedance value. A single matching device has been found sufficient to transform the impedance at the junction point of the antenna structure and the transmission line in spite of an inherent characteristic whereby the driving impedance of the antenna varies over the frequency range. By means of a matching structure, it has been possi-

2

ble to obtain an impedance at the junction point which averages 51.5 ohms over the FM frequency range.

Since it is customary in FM transmitters to employ a plurality of bays, the present invention contemplates the use of as little as two bays, each having a conservative power rating of 5 kw.

It is therefore, an object of the present invention to provide a simple, lightweight and inexpensive transmitting antenna designed for operation in the FM range of 88 to 108 megacycles.

It is a still further object of the present invention to provide an FM transmitting antenna having a substantially constant field intensity pattern throughout the FM range without utilizing a multiplicity of tuning and matching devices.

It is a still further object to provide a multiple bay antenna having a relatively simple antenna feed system.

20 Still another object of the present invention is to provide a simple assymmetric FM antenna having a substantially circular horizontal field intensity pattern.

25 A still further object of the present invention is to provide an FM antenna arrangement to permit insulation resistance checks without disconnecting the antenna radiating elements.

30 Still another object of the present invention is to provide a simple FM antenna which may be attached to existing antenna tower structures.

35 A still further object of the present invention is to provide an FM antenna design suitable for mass production whereby a single design may be adjusted or pre-tuned at the factory for any frequency of operation.

40 Still another object of the present invention is to provide an improved FM antenna structure which may employ a plurality of bays and which has a standing wave ratio ranging from 1.2 to 1.4 in the range of 88 to 108 megacycles.

45 Other and further objects of the present invention subsequently will become apparent from reference to the following description taken in conjunction with the drawings wherein:

Figure 1 is a perspective view of a mounted FM antenna employing the principles of the present invention;

Figure 2 is a detailed view partially in cross section of the upper antenna bay;

50 Figure 3 is a bottom view of the upper antenna bay;

Figure 4 is a detailed view partially in cross section of the lower antenna bay;

55 Figure 5 is a graphical representation of the horizontal field intensity pattern;

Figure 6 is a schematic showing of the electrical circuit of the antenna; and

Figure 7 is a schematic showing of a modified electrical circuit for the antenna.

Most existing antenna structures which are to serve for the transmission of both FM and AM radiations are adapted to support an additional member such as an I or H beam 11 shown in Figure 1. The support mast 11 preferably is a steel H beam so oriented that the well on one side forms a protective enclosure for a transmission line 12 whereas the opposite side or well of the H beam serves as enclosure for a power conductor 13 shown in Figure 3. The H beam 11 carries at its top a beacon light 14 of any suitable type which meets the requirements of the Federal Communications Commission regulations. In order to service the light and the antenna radiators, the H beam is provided with a plurality of steps 15 which preferably are placed in those portions of the walls of the well containing the power conductor 13.

For the purpose of illustrating the present invention there has been shown in Figure 1, a transmitting antenna embodying an upper bay 16 and a lower bay 17. The upper bay 16 preferably is carried by a support plate 18 which is secured in position by a plurality of straps 19 extending across the flanges of the H beam 11. The strap construction, subsequently to be described, permits vertical movement of the upper bay 16 to allow for the difference in expansion of the copper transmission line 12 and the steel H beam 11. Such an arrangement also permits the mast 11 to bend without unduly straining or stressing the transmission line 12.

The lower bay 17 is also mounted on a supporting plate 21 which may be retained in position by a strap or if desired the plate 21 may be rigidly connected to the H beam 11.

Each bay consists of two radiating elements arranged in the form of a truncated V. Each element is preferably formed of a telescopic structure which is most conveniently formed of a plurality of tubes. The larger tube has a length which is selected for the highest frequency operation of an antenna of this type within the afore mentioned FM range of frequencies. The base of each of these larger conductors is connected to the outer conductor of the coaxial transmission line 12. The outer extremity of this larger tube of one of the radiators is also connected by a conductive element to the outer conductor of the coaxial transmission line 12. The other larger tube of the radiating elements is connected by a conductive strap to the inner conductor of the transmission line 12.

Certain details of the antenna structure will become more apparent by reference to the detailed figures. In Figure 2, there is shown the upper bay structure which is supported by a mounting plate 18. The mounting plate 18 carries the stud 23 which is retained in position by a plurality of bolts or cap screws 24. The stud 23 supports the outer tube or primary radiating element 25. This tube 25 has a length which is determined by the highest frequency radiation in an antenna of this type within the FM frequency range. The outer extremity of the tube 25 is connected to a conductive strip or power lead 26 which terminates at a binding post 27 carried by an insulator 28. The tube 25 carries an extension tube 29 arranged to telescope relative to the tube 25 so that the overall effective length of the radiating element provides a tuned

radiator at the transmitting frequency. The outer extremity of the tube 29 may be sealed by a cap or other closure member 31.

The insulator 28 shown partially in cross section is carried by a plate 32 retained in position by suitable cap screws 33 which pass into threaded openings in the mounting plate 18. The mounting plate 18 is provided with a suitable opening for receiving a junction box 34 which may be secured in position by any suitable manner including silver soldering. In order to provide a weather-proof and gas tight seal an O ring 35 is interposed between the mounting member 32 and the junction box 34.

From the cross sectional view of the insulator 28 it will be seen that the insulator has a hollow portion which carries a central conductor stem 36 arranged to receive a banana plug 37. The banana plug 37 is a bifurcated cylindrical portion of a conductor 38 which is secured to a conductor 39. The conductor 39 is insulated by a plurality of beaded insulators 41 and held in spaced coaxial relation to the inner conductor 42 of the coaxial line 12. The inner conductor 42 of the transmission line section 43 is mounted on spaced insulator beads 44 carried within the outer conductor 45. The conductive member 39 extends within the inner conductor 42 of the transmission line section 43 a sufficient distance to form a capacitor of the proper value. The outer conductor 45 terminates in a mounting flange 46 which is coupled by suitable bolts 47 to a cooperating mounting flange carried by the other section of the transmission line 12. The series capacitor interposed between the inner conductor 42 and the transmission line and the primary radiating element 25 serves to produce several advantages. Since one element of each bay is insulated by a capacitor it is possible to make resistance checks without disconnecting the radiating elements. The series capacitor also provides positive reactance elements in the direct driving impedance so that the antenna element is operated at a frequency several megacycles above resonance. Operation at a frequency above resonance stabilizes the horizontal field intensity pattern.

By reference to Figure 3 it will be seen that the primary radiating element 48 is provided with a telescopic portion 49 which has an end cap 51. The outer extremity of the larger conductor 48 is connected by a conductive strip 52 to the mounting plate 18 by means of a cap screw 53. From this it becomes apparent that each of the fixed extremities of the radiating elements is connected to the mounting element 18 which is in electrical conductivity with the outer conductor 45 of the coaxial transmission line section 43.

The details of the construction of the lower bay are apparent from Figure 4. The mounting plate 21 carries a stud 54 held in position by a suitable cap screw 55. The stud 54 carries the larger conductor or tube 56 which supports a telescopic portion 57 having its end sealed by a cap 58. The outer extremity of the primary conductor 56 of the radiating element is connected by a conductive strip 59 to the binding post 61 carried by the insulator 62. The insulator 62 is supported by a plate 63 secured in position by suitable cap screw 64 which engages threaded holes in the mounting plate 21. The mounting plate 21 adjacent the insulator 62 is provided with a suitable opening for receiving a portion of the junction box 65 which is retained in position by suitable fastening means as by silver

soldering. A suitable O ring 66 is compressed between the junction box 65 and the mounting or support plate 63 of the insulator 62 to provide a gas tight seal.

The insulator 62 which has a hollow portion is provided with a central conductor 67 having a hollow extremity for receiving the banana plug end 68 of a conductive conductor 69. The conductive conductor 69 extends through an insulated bushing 71 which is fitted into an aperture 72 in the inner conductor 73 of the coaxial transmission line section. The conductive conductor 69 is connected to a conductor rod 74 which is supported in coaxial relation to the inner conductor 73 by means of a plurality of insulating beads 75. The conductive rod 74 together with the inner conductor 73 of the coaxial transmission line forms a capacitor which thereby insulates the radiating element from the transmission line so that resistance measurement may be made without disconnecting the antenna elements.

The inner conductor 73 is mounted in coaxial relation with respect to the outer conductor 76 by means of a plurality of insulating beads or supports 77. Because of the junction box 65 the outer conductor 76 has a portion cut away to receive this junction box. The junction box 65 is provided with suitable grooves which are filled with silver solder 78 so as to provide a gas tight connection between the junction box and the several portions of the outer conductor 76. The outer conductor 76 at either end is provided with mounting flanges 79 for connection to cooperating sections of the coaxial transmission line. The upper and lower bays are spaced one wave length apart and hence sufficient coaxial conductor is employed to provide this spacing with the frequency at which the antenna is to operate.

In order to match the impedance of the antenna to the impedance of the coaxial conductor which interconnects the lower bay with the transmitter, the inner conductor 73 is provided with a sleeve 81. The sleeve 81 is a quarter wave length long. The impedance of the present antenna construction is high as compared to other constructions since this construction involves the folded dipole principle. The use of this principle minimizes unbalanced currents. Furthermore, the higher impedance makes it possible to feed only one half of the system with energy. Hence, as previously described, one of the radiating elements has one end at an intermediate point thereon connected to the outer conductor of the transmission line. It will also be noted that in antennas of this type, where the effective operating length is about one quarter wave length, the highest voltage appears at the outer extremity or the open end. Therefore, it is desirable to keep these open ends as far apart as possible for all frequency values. Due to the truncated V construction, these desirable requirements are met and there has been provided an excellent safety factor. Thus, any tendency toward flash over is minimized.

In the development of the present antenna, it was found that the present construction avoids some of the disadvantages occurring in assymetrical antenna structures. It has been found that the present antenna provides a power gain of 1.6 to 1.8 and a favorable standing wave ratio of 1.2 to 1.4 throughout the frequency range of 88 to 108 megacycles.

Referring to Figure 5 of the drawing, there is shown a typical horizontal field intensity pattern

by the curve A in relation to the physical orientation of the radiating elements. Measured radiation patterns show that the greatest deviation from circularity at any frequency is 1.5 decibels. The particular pattern illustrated in the drawing is for a frequency in the center of the FM band.

Figure 6 is a schematic showing of the electrical circuit from which it becomes apparent that a distance of one wave length separates the upper and lower bays. It also is apparent that the conductor portion which includes the impedance matching section immediately beneath the lower bay is of the order of one quarter wave length long. From the circuit diagram, it also is apparent that resistance measurements may be made without disconnecting the radiation elements. These resistance measurements test the insulation resistance of the feed line.

An antenna constructed in accordance with the present invention is tuned at the factory by adjusting the telescopic members in the radiating elements of each bay. These members are then soldered in place to hold the tuning. If, at any time, the frequency of operation of the transmitter is to be changed, the antenna may be readily tuned by unsoldering the telescopic members, adjusting them accordingly and resoldering them in position.

To permit movement of the base 18 of Figures 1, 2 and 3 relative to the H beam 11, the base 18 is held in position by two pairs of straps 19. Each strap terminates in an apertured portion bent at right angles to the body thereof so that suitable bolts or cap screws can be inserted through the apertures. The bolt or cap screw at one end of each strap engages the base 18. At the other end of each strap the bolt or cap screw engages an anchor stud plate 22 which is welded at right angles to the flange of the H beam 11. For convenience in manufacture and installation, it is preferable to have each bay supported in this manner, and this construction is of definite advantage where more than two bays are installed.

While a preferred arrangement for single or multiple bay antennas has been described and shown in Figures 1 to 6, another arrangement may be employed. This other arrangement is shown schematically in Figure 7 and may be of advantage where an economical single bay antenna is desired. In such case the construction shown in Figures 2 and 3 would be modified by eliminating the conductors 26 and 52, and by mounting the radiating element 48, 49 on an insulator so that the end of the tube 48 adjacent the insulator would be connected to the binding post 27.

While for the purpose of illustrating and describing the present invention a particular embodiment has been illustrated in the drawings, it is to be understood that the invention is not to be limited thereby, since such variations in the construction and in the instrumentalities employed are contemplated as may be commensurate with the spirit and scope of the invention as defined in the accompanying claims.

What I desire to protect by United States Letters Patent is claimed as follows:

1. An asymmetric antenna system having a generally circular horizontal radiation pattern comprising a single transmission line connected to a plurality of bays, each bay comprising a pair of generally horizontal conductors arranged at an angle to each other to form a truncated V,

the fixed end of each of said conductors being connected to one of said conductors of said transmission line, means connecting the other conductor of said transmission line to a point intermediate the ends of one of the other horizontal conductors, and a capacitor interposed between said transmission line and said second-mentioned conductor of each bay.

2. An asymmetric antenna system having a generally circular horizontal radiation pattern comprising a single co-axial transmission line connected to a plurality of radiating bays, each bay comprising a pair of telescopic members arranged at an angle to each other in a generally horizontal plane so as to form a truncated V, the fixed end of each of said conductors being connected to an outer conductor of said coaxial transmission line, means interconnecting the inner conductor of said transmission line with a point intermediate the ends of one of said horizontal conductors of each bay, a capacitor interposed between said inner conductor of said transmission line, and said latter mentioned conductor of each bay, and an impedance matching section connected immediately beneath the lower main bay.

3. An antenna consisting of a plurality of bays connected to a coaxial transmission line, each bay comprising a pair of generally horizontal linearly extending radiating elements mounted on a base to form a truncated V, one of said elements being connected to the outer conductor of a transmission line and the other element being connected through a capacitor to the inner conductor of the transmission line, said bays being spaced a wave length apart, an H beam for supporting said bases, and means connecting said bases to said H beam for limited vertical movement relative thereto.

4. An antenna comprising a coaxial transmission line, a pair of generally horizontal radiating conductors mounted upon a base, said conductors being arranged at an acute angle to each other to form a truncated V, the fixed end of one of said conductors being connected to the outer conductor of said transmission line, and means connecting the inner conductor of transmission line to said other horizontal conductor.

5. An antenna comprising a coaxial transmission line, a pair of generally horizontal radiating conductors mounted upon a base, each of said conductors being formed of two telescopic members for adjustment in accordance with the frequency to be transmitted, said conductors being arranged at an angle to each other to form a truncated V, the fixed end of one of said conductors being connected to the outer conductor of said transmission line, and means connecting

the inner conductor of said transmission line to a point intermediate the ends of said other horizontal conductor.

6. An antenna comprising a coaxial transmission line, a pair of generally horizontal radiating conductors mounted on a base, each of said conductors being formed of a fixed member and a movable member arranged telescopically for adjustment in accordance with the frequency to be transmitted, said conductors being arranged at an angle to each other to form a truncated V, the fixed end of one of said conductors being connected to the outer conductor of said transmission line and the inner conductor of said transmission line being connected to a point intermediate the ends of said other horizontal conductor adjacent the outer end of the fixed member thereof.

7. An asymmetric antenna having a generally circular horizontal radiation pattern comprising a coaxial transmission line connected to a plurality of bays, each bay comprising a pair of linearly extending horizontal radiating conductors arranged at an angle to each other to form a truncated V, each of said conductors being formed of two telescopic members for adjustment in accordance with the frequency to be transmitted, the fixed end of each of said conductors being connected to the outer conductor of said transmission line, and capacitor means connecting the inner conductor of said transmission line to said other horizontal conductor intermediate the ends thereof adjacent the outer end of the fixed supporting section of said telescopic member.
